UNITED STATES PATENT OFFICE.

JOSEPH J. MAGRADY, OF CHICAGO, ILLINOIS.

ADJUSTABLE LOCKING AND SEALING DEVICE FOR USE ON SCALES.

Application filed July 12, 1922. Serial No. 574,500.

To all whom it may concern:

Be it known that I, JOSEPH J. MAGRADY, a citizen of the United States of America, residing at Chicago, in the county of Cook and

5 State of Illinois, have invented certain new and useful Improvements in Adjustable Locking and Sealing Devices for Use on Scales, of which the following is a specification.

10 My present invention relates generally to scales and more particularly to what are commonly known as platform scales operating through a series of levers located below the platform and commonly adjusted in an uncertain haphazard manner by methods which are open to the manipulation of any one, skilled or unskilled, honest or otherwise, and my object is the provision of means whereby certain definite and accurate

15 ·20 ·25 ·30 ·35 ·40 ·45

adjustments may be quickly and easily made and wherein the adjustable parts when properly positioned may be locked against unwarranted tampering and sealed in place.

More especially my invention aims to simplify the adjustment of platform scale levers, promote accuracy and speed of adjustment and insure uniformly accurate operation as well as avoiding unwarranted tampering and adjustment.

30 My invention is shown in the accompanying drawing which forms a part of this specification, and in which,

Figure 1 is a side elevation of a scale pit lever showing my improvements applied thereto and sealed,

Figure 2 is an end view of the scale pit lever,

Figure 3 is a side view, partly in elevation and partly in vertical longitudinal section showing my improvements applied as in Figure 1,

Figure 4 is an end view of the complete device, and

Figure 5 is a detail face view of the adjusting wheel.

Referring now to these figures, I have shown at 10 a lever which may be one of the main pit levers or the central cross lever of platform scales, provided at one end with a 50 nose iron 11 commonly adjusted by driving the same lengthwise of the lever and securing the same in adjusted position by set screws and the like to vary the effective length of the lever and in this way cure light 55 or heavy weighing.

The usual method of adjustment is not

conducive to accuracy and is open to unskilled and dishonest persons, and for these reasons among others, I propose a nose iron 11 having a rectangular bore 12 receiving a 60 similarly shaped and reduced extension 13 of the lever 10 and provided with depending spaced ears 14. These ears 14 have openings 14^a alined with one another and with an opening 15 through a lug 16 depending from the lever 10 adjacent to the inner end of extension 13.

The lug 16 of the lever supports the inner end of an outstanding adjusting rod 17 threaded throughout its length whose inner end extends through the lug opening 15 and is locked by nuts 18 abutting opposite sides of the lug and threaded on the rod. The outer portion of the rod 17 extends loosely through the openings 14^a of the ears 14 and receives an adjusting wheel 19 threaded thereon and disposed between the ears 14 by which it is confined against lengthwise displacement with respect to the nose iron 11.

Thus by rotating the wheel 19 it is obvious the nose iron 11 may be accurately, quickly and easily adjusted on the lever extension 13. The adjusting wheel has an annular series of apertures 20 as will be seen in Figure 5, while as seen in Figures 2 and 4, the depending ears 14^a of the nose iron 11 have laterally spaced apertures 14^b, for the reception of the parallel extensions of a sealing wire 21 which when threaded through certain alined apertures 20 of the adjusting wheel, may have its free ends securely connected by a lead seal 22 as in Figure 1, thus sealing the adjustable parts in adjusted position against tampering without breaking the seal.

I claim:

1. A scale lever having a nose iron adjustable thereon and also having an adjusting rod, and an adjusting wheel threaded on said rod and mounted in the nose iron, and means for locking the adjusting wheel in adjusted position.

2. A scale lever having a nose iron adjustable thereon and also having an adjusting rod, and an adjusting wheel threaded on said rod and mounted in the nose iron, said wheel and said nose iron having apertures adapted to aline, and a seal threaded through said apertures to seal the wheel in adjusted position.

3. A scale lever, an adjustable nose iron thereon, means including an adjusting wheel in the nose iron for adjusting the latter, and

means engageable with said wheel and a portion of the nose iron for locking the wheel against movement.

4. A scale lever, an adjustable nose iron thereon, and normally sealed means for adjusting the nose iron on the lever, including an adjusting member carried by the nose

iron and a sealing member engageable with the said adjusting member and with the nose iron.

In testimony whereof I have affixed my signature.

JOSEPH J. MAGRADY.
